UNITED STATES PATENT OFFICE

OTTO S. NELSON AND WALTER M. WILLY, OF MITCHELL, SOUTH DAKOTA, ASSIGNEES
TO HANDY-HAUL AUTO TRUNK COMPANY, OF MINNEAPOLIS, MINNESOTA, A COR-
PORATION OF SOUTH DAKOTA

COMBINED TRUNK AND LUGGAGE CARRIER

Application filed October 25, 1928. Serial No. 315,006.

This invention relates to a combined trunk and luggage carrier and has for its primary object to provide, in a manner as hereinafter set forth, a device adapted to be secured to the body of a motor vehicle, which is normally in the form of a trunk for the reception of miscellaneous goods and packages, and which may be extended when desired in order to provide a luggage carrier for supporting grips, camping equipment and the like.

A further object of the invention is to provide a device which may be selectively converted into a trunk or luggage carrier as aforesaid including novel means for latching the parts thereof in their selected positions.

With the foregoing and other objects in view the invention consists of the novel construction, combination and arrangement of parts as hereinafter more particularly described and illustrated in the accompanying drawings, wherein is shown an embodiment of the invention, but it is to be understood that changes, variations and modifications may be resorted to which fall within the scope of the invention as claimed.

In the accompanying drawings, in which like numerals are employed to designate like parts throughout the same:

Figure 1 is a perspective view of the device shown in extended position.

Figure 2 is a vertical section through the device in extended position, but with the end gate therefor shown in raised position.

Figure 3 is a vertical section through the device shown in closed position.

Figure 4 is an enlarged, detailed section taken on line 4—4 of Figure 2.

Figure 5 is an enlarged, fragmentary rear elevation of the embodiment illustrated in Figure 2.

Figure 6 is an enlarged, detailed perspective view of one of the locking members for securing the device in closed position.

Referring to the drawings in detail, the numeral 1 designates generally a stationary trunk portion consisting of a bottom member 2, a rear wall member 3, and a pair of side wall members 4. Hingedly connected

to the upper edge of the rear wall member 3 is a lid 5, which is formed at its forward edge with a depending flange 6 and at its side edges with a pair of depending flanges 7. Each of the side flanges 7 is of the same width at its forward end as the width of the forward flange 6 and the free edge of the side flange 7 inclines towards the top member 5 from the forward end of the flange to the rearward end thereof. The upper edges of the side members 4 incline upwardly from front to rear and spaced from the upper edge thereof, each side member 4 is formed with an offset 8, against which the free edge of a side flange 7 abuts when the lid 5 is in closed position. Due to the inclination of the free edges of the side flanges 7 towards the top 5 from the forward ends to the rearward ends of said flanges, the top 5 is disposed in a horizontal position when the free edges of the flanges 7 are seated on the offsets 8.

Hingedly connected to the forward edge of the bottom member 2 is the bottom member 9 of a movable extension indicated generally by the numeral 10. Secured to each side edge of the bottom member 9 and extending vertically therefrom is a side member 11, the upper, forward corner of which is rounded, as indicated at 12. Projecting from the inner face of each side member 11 is an upper pair of horizontally aligned studs 13, and a lower pair of horizontally aligned studs 14. Positioned against the inner face of the side member 11 is an extension slide 15, which is formed with a pair of upper, horizontally aligned, elongated slots 16 for the passage of the studs 13 therethrough, and which is further formed with a pair of lower, horizontally aligned, elongated slots 17 for the passage of the studs 14 therethrough. The studs 13 and 14 extend loosely through the slots 16 and 17 and are formed with suitable enlarged free ends to prevent the same from being withdrawn through the slots. The rearward edge of each extension slide 15 is formed with a spaced, returned portion 18 which fits within the channel of a channel member 19, one of which is secured

to the inner face of each side member 4, adjacent the forward edge thereof.

Pivots secured as at 20 to the inner face of each extension slide 15, adjacent the rearward edge thereof, is a locking element 21 which has a stud 22 extending therethrough and projecting from the inner face thereof for insertion through an opening 23 formed through the extension slide 15 and a similar, registering opening 24 formed in the channel member 19. The element 21 is formed of spring material in order that the stud 22 may be withdrawn from the openings 23 and 24 when desired.

Hingedly connected to the forward edge of the bottom member 9 is an end gate 25, the side edges 26 of which are rolled inwardly to provide elongated apertures for the reception therein of latching pins 27. Each of the rolled edges 26 is formed with a cut out portion 28 to receive therein a vertically apertured boss 29, one of which is secured to the inner face of each side member 11, adjacent the forward edge thereof. When the end gate 25 is raised to the position shown in Figure 2, the apertures through the rolled edges 26 and bosses 29 are brought into registry, in which condition the pins 27 may be inserted through the apertures.

When the device is in extended position as shown in Figure 2, the studs 13 and 14 are located at the forward extremities of the slots 16 and 17. When the extension member 10 is moved about its hinged connection to close the same, the rearward edges of the extension slide 15 are brought into contact with the upper face of the bottom member 2, which causes a relative movement between the extension slides 15 and side members 11 causing the studs 13 and 14 to travel through the slots 16 and 17 until they reach the rearward or lower extremities of the slots, when the device is in closed position as shown in Figure 3.

If it is desired to retain the end gate 25 in parallel relation with the bottom 9 when the device is in closed position as shown in Figure 3, the end gate 25 is moved to the parallel position before the extension member 10 is moved about its hinge to close the device. When the device is in closed position, the relative movement between the extension slides 15 and side members 11 extends the forward or upper edges of the slides 15 beyond the rearward or lower edge of the end gate 25. The forward or upper marginal portion 30 of each slide 15 is offset inwardly and with the device in closed position as shown in Figure 3, the offset portions 30 bear against the end gate 25 and prevent the latter from becoming displaced.

The movable extension member 10 is provided at each lower side edge thereof with an angle member 31, one wing of which is spaced from the outer face of the side members 11.

When the extension member 10 is moved about its hinge to close the device, the forward edge 32 of each side member 4 is received within a space between the angle member 31 and a side member 11.

The lower face of the bottom member 9, adjacent the forward edge thereof, is formed with an offset 33 which is brought into horizontal alignment with the forward ends of the offsets 8 when the extension element 10 is moved about its hinge into closed position. When the lid 5 is closed, with the element 10 in closed position, the lower edge of the flange 6 abuts the offset 33 and the lower marginal portion of the flange 6 overlaps the upper marginal portion of the bottom member 9. The angle members 31 are of appropriate length to have their upper ends terminate adjacent the offsets 8 and 33 when the element 10 is in closed position.

It is to be understood that the form of the invention herewith shown and described is to be taken as the preferred example of the same and that various changes in the details of construction may be resorted to without departing from the spirit of the invention or the scope of the appended claims.

What we claim is:

1. A device of the character described comprising, a stationary trunk portion having a bottom, rear, and a pair of side walls, a movable extension element hingedly secured to said bottom wall and consisting of a bottom, and a pair of side members, said side members being embraced between said side walls when the extension element is in closed position, an extension slide slidably secured to the inner face of each side member, a stop formed on the inner face of each of said side walls, and means on said slide coating with said stop for limiting the movement of said extension element in its extended direction.

2. A device of the character described comprising, a stationary trunk portion having a bottom, rear, and a pair of side walls, a movable extension element hingedly secured to said bottom wall and consisting of a bottom, and a pair of side members said side members being embraced between said side walls when the extension element is in closed position, an extension slide slidably secured to the inner face of each side member, a stop formed on the inner face of each of said side walls, and a spaced, returned portion formed on each of said slides for engagement with said stops to limit the movement of said extension element in its extended direction.

3. A device of the character described comprising, a stationary trunk portion having a bottom, rear, and a pair of side walls, a movable extension element hingedly secured to said bottom wall and consisting of a bottom, and a pair of side members, said side members being embraced between said side walls when the extension element is in closed position, an

- extension slide slidably secured to the inner face of each side member, a stop formed on the inner face of each of said side walls, a spaced, returned portion formed on each of said slides 5 for engagement with said stops to limit the movement of said extension element in its extended direction, and means coacting with said stops and slides for retaining said extension element in extended position.
- 10 4. A device of the character described comprising, a stationary trunk portion consisting of a bottom, rear, and a pair of side walls, an extension element hingedly secured to said bottom wall to permit movement of said element from closed to extended position, said element consisting of a bottom, and a pair of side members, said side members being embraced between said side walls when the extension element is in closed position, each of 15 said side members having a stud projecting from the inner face thereof, an extension slide adjacent each side member and formed with a slot for the reception of said studs therethrough, a stop formed on the inner face of 20 each of said side walls, and means on said slides coacting with said stops for limiting the movement of said element in its extending direction.
5. A device of the character described comprising, a stationary trunk portion consisting of a bottom, rear, and a pair of side walls, a movable extension element hingedly secured to said bottom wall to permit movement of 25 said element from closed to extended position, said element consisting of a bottom, and a pair of side members, said side members being embraced between said side walls when the extension element is in closed position, an end gate hingedly secured to the forward 30 edge of said bottom member, an extension slide slidably secured to the inner face of each of said side members, means for selectively securing said extension element in closed and extended positions, and an offset formed on 35 each slide and overlying a marginal portion of said end gate to maintain the latter in parallel relation to said bottom member when said extension element is in closed position.
6. A device of the character described comprising, a stationary trunk portion having a bottom, rear, and a pair of side walls, a movable extension element hingedly secured to said bottom wall to permit movement of said element from closed to extended position, 40 said element consisting of a bottom, and a pair of side members, stops adjacent the forward edges of said side walls, and means carried by the side members and coacting with said stops to position the bottom member horizontally when the extension element is in extended position, said means being slidably connected with the side members whereby said bottom member may assume a vertical position when the extension element is closed 45 with all parts of the latter disposed above

the lowermost extremity of the stationary trunk portion.

In testimony whereof, we affix our signatures hereto.

OTTO S. NELSON
WALTER M. WILLY.
